(57) **CLAIM**

The ornamental design for a display screen with graphical user interface, as shown and described.

DESCRIPTION

FIG. 1 is a front view of a display screen with graphical user interface showing our new design;

FIG. 2 is a front view of a display screen with graphical user interface of FIG. 1 with regions for enlargement indicated by broken-line indicia;

FIG. 3 is an enlarged view of a region indicated by the broken-line indicia in FIG. 2; and,

FIG. 4 is an enlarged view of a region indicated by the broken-line indicia in FIG. 2.

The “FIG. 3” and “FIG. 4” indicia shown in FIG. 2, as well as the rectangles both identifying and displaying the enlarged regions of the graphical user interface form no part of the claimed design. The broken line showing of the alphanumeric characters, the remainder of the graphical user interface, and display screen is for environmental purposes only and forms no part of the claimed design.
